UNITED STATES PATENT OFFICE.

WILLIAM SMITH, AND FRANK CAMPBELL, OF GLASGOW, SCOTLAND.

CHALK ATTACHMENT FOR BILLIARD-TABLES.

No. 905,380.

Specification of Letters Patent.

Patented Dec. 1, 1908.

Application filed January 11, 1908. Serial No. 410,330.

To all whom it may concern:

Be it known that we, WILLIAM SMITH, of 181 Main street, Bridgeton, Glasgow, Scotland, billiard-room proprietor, and FRANK CAMPBELL, of 56 Bain street, Glasgow, Scotland, billiard-room proprietor, subjects of the King of Great Britain, have invented a certain new and useful Chalk Attachment for Billiard-Tables, of which the following 10 is a specification.

At present it is usual in billiard saloons and other places to have chalk suspenders, the chalk being slung from a device attached to the ceiling of the room. Such suspenders 15 are inconvenient and in the fitting of the same to the ceiling or other part more or less damage is done.

Under our invention we provide an arrangement whereby the chalk is attached to 20 the billiard table and is automatically drawn up under the ledge of the table by means of a weight (or spring), the connection of the chalk and weight being effected by means of a flexible connection such as a cord or chain 25 or its equivalent and a steel wire or spring or its equivalent by means of which the chalk is prevented from striking against the table when being automatically drawn up under the table ledge.

30 In order that the invention may be clearly understood we have hereunto appended explanatory drawings which show by way of example, a method of carrying out the invention.

35 Figure 1 is a plan of a billiard table with the chalk attachments indicated in dotted lines. Fig. 2 is a longitudinal section taken on the line 2. 2. Fig. 3. Fig. 3 is a cross section taken on the line 3. 3. Fig. 2. Figs. 4 40 and 5 are respectively, a front and sectional view showing the chalk attached to the spring wire. Fig. 6 is a similar view looking on the side thereof and shown with the chalk pulled up as when in use. Fig. 7 is a part 45 section and part side view showing the connection of the wire with the cord. Fig. 8 is a view showing part of an under rail of the table having an eye piece shown thereon. Fig. 9 is a view of one of the weights. Figs. 50 10 and 11, show respectively, an end and side view of a clip with chalk therein. Figs.

12 and 13 are similar views of a slightly modified form of clip and chalk. Fig. 14 is a cross section of a "French" billiard table and shows a special fitting for use in connection with such tables.

Referring to Figs. 1 to 3 the billiard table is made as usual with a top *a*, side rails *b*, end rails *c*, longitudinal under bars *d*, transverse under bars *e* and legs *f*, and may be fitted with six chalks and attachments therefor, two being fitted at each side and one at each end of the table. Stretched between the two longitudinal bars *d* at the center of the table is a cord or strip *g* which is, at its center, knotted or otherwise secured to the ends of two cords or the like *h*. Each cord *h* passes through a hole provided in the transverse bars *e* and is secured to the end of a spring steel wire *i* which passes through a hole provided in the end rail of the table and to the outer end of this wire and outside of the table frame a small clip carrying a block of chalk *j* is secured by means of a short chain *k*. Between the cord or the like *g* and the transverse bar *e*, each of the cords *h* passes through a loop *l* on a weight *l* (Fig. 9) which latter draws the cord *h* downwards and thereby draws the chalk beneath the table ledge.

The side chalks *j* are each secured in the same way to a spring steel wire *i* by means of a chain *k*. The wires *i* pass through the side rails *b* and the inner end of each of these wires is connected by means of a cord *h* with the inner end of the wire in line with it at the opposite side of the table, the cords *h* being provided, between the longitudinal bars *d*, with weights *l* having loops *l* thereon through which the cords pass, each 90 weight *l* drawing one of the cords *h* downwards and thereby drawing two of the chalks beneath the table ledge.

The weights *l* which are shown clearly at Fig. 9 may be of any suitable form and material and are made sufficiently heavy to draw the chalks inward with the necessary rapidity.

The holes in the under bars *d*, *e*, of the table through which the cords *h*, *h* pass are 100 each provided at one or both sides of the bar with a small plate *m* which has a hole

m^1 therein and is secured to the bar by means of screw nails m^2 .

The wires i are each secured to a cord h or h^1 by means of the arrangement shown at Fig. 7. The inner end of the wire is screwed at i^1 and the end of the cord h or h^1 is tied to an eye or ring n^1 which is formed on the end of a thimble piece n , and the said end i^1 of the wire is screwed into a hole n^2 provided therefor in the thimble piece. The end of the thimble piece n comes in contact with the inner side of the end or side rail of the table when the chalk is drawn outwards and thereby acts as a stop.

15 The end or side rails of the table, as shown at Fig. 5, have the hole through which the wires i pass each fitted with a bush or lining o , which is made with a collar o^1 at one end and is tapered externally, being driven into the rail from the outside thereof until the collar butts against the face of the rail.

20 The wires i are secured to the chalk clips as shown at Figs. 4 and 5. The end of each wire i is turned back so as to form a loop to which the chain k is secured and on the end of the wire i is a wooden or hard rubber or like ball or piece p , the wire being passed through a tapered hole in the ball which is 25 then drawn tightly over the joint formed between the wire i and chain k . Fitted between the ball p and the table rail is a guide or stop ring q which is screwed into the ledge of the table near the outer edge thereof and 30 is made with a shoulder q^1 so as to insure its being screwed up to the proper level. The chain k has a swivel k^1 of any suitable form fitted near the center thereof, and this swivel allows the chalk to hang freely and prevents 35 the chain becoming twisted and damaged.

40 The clips, by means of which the chalks are secured to the chains k , are shown at Figs. 10 and 11 and in a modified form at Figs. 12 and 13. The chalk j shown at Figs. 45 10 and 11 is made rectangular, both ends or one end only, being adapted for use, and fitted round the center or near one end of the chalk is a strip or band r which may be made with a hinge r^1 as shown or without a 50 hinge. The chalk j^1 , shown at Figs. 12 and 13, is somewhat similar but is made cylindrical and the strip or band r^2 thereon is shown without a hinge. The ends r^3 and r^4 of the strips or bands r and r^2 are turned 55 upwards and through these ends bolts r^5 are passed and each strip or band is tightened round its chalk by means of a nut r^6 on its bolt r^5 . The chain k is secured to the bolt r^5 between the ends of the strip or band. 60 When the chalk is hung from one end the chain may be attached so that the chalk will hang vertically.

The fitting shown at Fig. 14 is for use with a billiard table without pockets or other

small tables where there are no under bars to support the cord. An eye s is screwed into each of the table side rails and a cord or wire or the like s^1 is stretched between these eyes, the cord or the like s^1 being made in halves and having therebetween a ring s^2 through which the cord connected with the weight and chalk passes.

65 Although the invention has been described with reference to a table fitted with six chalks it is of course obvious that the number of chalks used may be increased or diminished as desired and the arrangement can be fitted in a variety of ways. In lieu of the weights we may use spiral or other springs for drawing the chalks beneath the 70 table ledge, and in lieu of the spring wire we may use any other suitable and well known spring connection; the wire, however, we find to answer the purpose excellently.

75 Having now fully described our invention what we claim and desire to secure by Letters Patent is:—

80 1. The combination with a billiard table of a chalk holding clip, flexible means fitted beneath the table and connecting the chalk clip therewith, means for automatically drawing the said flexible means beneath the table top and spring means for preventing the clip striking against the table top.

85 2. The combination with a billiard table of a chalk clip, flexible and spring means fitted beneath the table and connecting the chalk clip therewith, means for automatically drawing the said flexible and spring 90 means beneath the table top, a stop on the table and a block with tapered hole therein adapted to engage therewith and prevent the flexible means being drawn too far beneath the table.

95 3. The combination with a billiard table of a chalk clip, flexible means fitted beneath the table, a spring wire connecting said means with the chalk clip, means for automatically drawing the said flexible means 100 beneath the table top, a screw stop on the table and a ball with tapered hole therein on the spring connection adapted to engage said stop.

105 4. The combination with a billiard table of a chalk clip consisting of a metal strip fastened by a bolt and nut, a chain connected to said clip, a spring, a cord connecting said spring with the table, a weight on the cord, a stop on the table and means 110 adapted to engage said stop.

115 5. The combination with a billiard table of a chalk clip, a chain, a cord under the table, a spring wire connecting the chain and cord, a weight on the cord, guides for the cord, a stop fitted to the table and a ball on said spring wire.

120 6. The combination with a billiard table

of a chalk clip, a chain with swivel, a cord under the table, a spring wire doubled at one end and screw threaded at its other end, a coupling socket connecting the cord and wire, guide means for the cord and wire, a ball with tapered hole therein fitted on the wire, a stop on the table, and means beneath the table for automatically pulling the cord.

In testimony whereof we affix our signatures in presence of two witnesses.

WILLIAM SMITH.
FRANK CAMPBELL.
